UNITED STATES PATENT OFFICE.

FREDERICK J. GERRARD, OF MONROE, NEBRASKA, ASSIGNOR OF ONE-HALF TO
CARL O. HART, OF MONROE, NEBRASKA.

PORTABLE FIRE-ESCAPE.

1,369,802.

Specification of Letters Patent.

Patented Mar. 1, 1921.

Application filed December 17, 1918, Serial No. 267,184. Renewed July 1, 1920. Serial No. 393,455.

To all whom it may concern:

Be it known that I, FREDERICK J. GERRARD, a citizen of the United States, residing at Monroe, in the county of Platte and State 5 of Nebraska, have invented certain new and useful Improvements in Portable Fire-Escapes; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15 This invention relates to new and useful improvements in fire escapes, and consists essentially in the provision of a casing having a reel about which a cable unwinds as the fire escape lowers, and the provision of 20 an automatic brake mechanism for regulating the speed of descent of the person being lowered with the fire escape.

The invention consists of further various details of construction, combination and 25 arrangement of parts which will be herein-after fully described, shown in the accompanying drawings and then specifically defined in the appended claims.

I illustrate my invention in the accompanying drawings which, with the letters of reference marked thereon, form a part of 30 this application and in which:

Figure 1 is a perspective view.

Fig. 2 is a central vertical sectional view 35 through the apparatus.

Fig. 3 is a central view showing the parts out of gear, and Fig. 4 is a sectional view on line 4—4 of Fig. 2.

Reference now being had to the details of 40 the drawings by letter:

A designates a casing in which the operative parts of the fire escape are mounted, which consists of a circular outlined friction band B secured to the inner surface of the 45 side wall of the casing. A frame C is mounted within the casing and E is a shaft journaled in suitable bearings in one of the side walls of the casing and said frame, and has a reel D fixed thereto and to which a 50 cable is fastened, designed to unwind upon the reel, said cable passing through the top of the casing, and having a hook F fastened at its end, which is designed to be secured to any stationary object, such as the frame

of a door or window within the building. 55 Fixed to said shaft is a gear wheel H which is in mesh with a pinion wheel I journaled on a stationary shaft K which has bearings in the opposite walls of the casing and in said frame. An anti-friction roller L is 60 journaled upon the stationary shaft K and has flanges L' at its ends. A centrifugal brake member M is pivotally mounted upon a pin N carried by a bar O which is fastened at one end to the face of said pinion wheel I. 65 A beveled brake shoe M³ is mounted upon one end of said member M and a weight M² upon the member adjacent to its opposite end, which end is beveled, as shown at M', to bear upon the band B. A spring Q is 70 fastened one end to said member and its other end to the outer free end of an arm O' projecting from said bar, the purpose of said spring being to normally hold the brake member so that a notched portion R of the 75 brake member will engage the anti-friction roller L which is journaled upon the shaft K, suitable washers S² being mounted upon the shaft K at either end of the friction roller and serving to prevent the brake member 80 coming in contact with the gear mechanism.

A hand operated brake member T is pivotally connected at T' inside the casing and has a concaved portion extending over the 85 gear wheel which is fixed to the reel carrying shaft, and T² is a coiled spring fastened at one end to the brake member T and its other end to said frame. Said member T is normally held by the spring T² in contact with 90 the teeth of the gear wheel H. Straps W are fastened to the casing and through which the legs of a person are adapted to be passed, and a second strap V is secured to the ends of the casing and designed to pass about the 95 body of a person using the fire escape, in the manner shown in Fig. 1 of the drawings.

In operation, the person using the fire escape sits upon the straps, as shown, and by releasing the brake member T the cable will 100 be allowed to unwind from the reel and the speed of the rotation of the reel will be governed. The centrifugally operated brake mechanism, when thrown against the inner surface of the brake band B, will have a 105 wedging frictional action and tend to slacken the unreeling of the cable, thus insuring a safe descent for the person using the appara-

tus. When the speed is reduced the parts will be returned to their normal positions, as will be readily understood.

What I claim to be new is:

- 5 1. A fire escape, comprising a casing, a shaft journaled therein, a gear and a reel fixed to said shaft, a stationary shaft and a pinion loosely journaled thereon and in mesh with said gear wheel, a bar secured to the face of said pinion, a pivotal spring pressed weighted brake member mounted upon said bar, and a brake shoe thereon, a stationary friction band within the casing and against which said shoe is adapted to 10 contact.
- 10 2. A fire escape, comprising a casing, a shaft journaled therein, a gear and a reel fixed to said shaft, a stationary shaft and pinion loosely journaled thereon and in 15 mesh with said gear wheel, a bar secured to the face of said pinion, a brake member pivotally mounted near the outer end of said bar, a beveled shoe upon the brake member adjacent to its pivotal end and a weight 20 near its opposite end, and spring connections between the bar and member, and a stationary friction band within the casing 25 near its opposite end, and spring connections between the bar and member, and a stationary friction band within the casing

against which said shoe is thrown by centrifugal force and adapted to have a wedging frictional engagement therewith.

30

3. A fire escape, comprising a casing, a shaft journaled therein, a gear and a reel fixed to said shaft, a stationary shaft and pinion loosely journaled thereon and in mesh with said gear wheel, a bar secured to the face of said pinion, a brake member pivotally mounted near the outer end of said bar, a beveled shoe upon the brake member adjacent to its pivotal end and a weight near its opposite end, and spring connections between the bar and member, and a stationary friction band within the casing 35 against which said shoe is thrown by centrifugal force and adapted to have a wedging frictional engagement therewith, and a 40 spring pressed pivotal hand brake engaging the teeth of said gear wheel.

40

In testimony whereof I hereunto affix my signature in presence of two witnesses.

FREDERICK J. GERRARD.
